(57) **CLAIM**

The ornamental design for a fan, as shown and described.

DESCRIPTION

1. Fan

1.1 : Perspective

1.2 : Perspective

1.3 : Front

1.4 : Back

1.5 : Left

1.6 : Right

1.7 : Top

1.8 : Bottom

1.9 Enlarged view of encircled portion 9 in 1.1

1.10: Enlarged view of encircled portion 10 in 1.2

1.11: Enlarged view of encircled portion 11 in 1.5

1.12 Enlarged view of encircled portion 12 in 1.6

1.13 Enlarged view of encircled portion 13 in 1.7

Dash-dash broken lines illustrate portions of the fan that form no part of the claimed design. Long dash-short dash broken lines encircling portions of the fan illustrate the boundaries of enlarged views and form no part of the claimed design.

1 Claim, 13 Drawing Sheets
